UNITED STATES PATENT OFFICE.

JOHN EVANS, OF BROOKLYN, NEW YORK.

WRENCH.

1,290,530.

Specification of Letters Patent.

Patented Jan. 7, 1919.

Application filed May 11, 1916. Serial No. 96,870.

To all whom it may concern:

Be it known that I, JOHN EVANS, a citizen of the United States, and a resident of Brooklyn, in the county of Kings and State of New

5 York, have invented a certain new and useful Improvement in Wrenches, of which the following is a specification.

My present invention relates to wrenches and more particularly to that class embodying a flexible device, such as a chain, to embrace the object to be rotated.

The principal object of my invention is to provide a wrench which is susceptible of quick adjustment to act upon objects, such 15 as pipes, nuts, bolts, or caps for containers of various sizes, and which will bring uniform pressure upon the periphery of objects, rendering the wrench well adapted for use on pipes or other objects which are collapsible, or those which are frangible such as 20 glass tubes.

Further objects of my invention are to provide a wrench which is adapted for use on objects having a highly polished surface, 25 and which become damaged to a degree rendering them useless, if acted upon by a wrench having serrated faces; and, to provide a wrench which is inexpensive to manufacture, and susceptible of ready repair.

30 Other objects of my invention will appear in the following detailed description, taken in connection with the accompanying drawings, forming a part of this specification, and in which drawing:

35 Figure 1 is a side elevation of a wrench constructed according to my invention and shown in operative relation to a pipe section.

Fig. 2 is a top plan view of the same.

40 Fig. 3 is a fragmentary perspective view of a portion of the operating lever.

Fig. 4 is a perspective view of a side of a master link.

In the drawings, wherein similar characters refer to similar parts throughout the several views, A designates a flexible device such as a chain; B an operating lever; and, C a master link.

45 As to the chain A, it is preferably made up of blocks 6 and connecting plates 7, of any suitable shape; and, pins 8, which may extend beyond the plate 7 to provide lateral projections 9, clearly shown in Fig. 2 of the drawings. These pins may be held in 55 place, in any suitable manner, such as by upsetting the end portions adjacent the

plate 7, this matter of retaining them in place rendering the chain susceptible of repair should any of its parts become broken or mutilated.

60

Referring first to the form of wrench shown in Fig. 1, the operating lever B comprises a head 10, rounded as at 11; a handle 12 extending from head 10; and, two laterally projecting abutments 13 in spaced 65 relation as clearly shown in Fig. 3. These abutments 13 are positioned laterally of the longitudinal axis of the lever and laterally of the portion 11 of the head 10. They may be provided with concave faces 14 at the bottom of the lever for engagement with the projections 9 of chain A.

70

Referring now to the master link C, it comprises sides 15 and cross-pins 16 and 17, the pin 16 passing through one of the blocks 75 6 of the chain A, and joining the sides 15 at one end portion of the link. The pin 17 joins the other end portions of the sides of said link, and may pass through a bore 80 18 in the lever B. The sides or master links 15 are provided at their free ends and at their inner faces with bosses or projections 19, facing each other and through which the pin 16 extends to hold the said block or link 6 of the chain A between the bosses. 85 The bosses 19 are provided, upon their inner sides facing the lever B with peripheral cam faces or loops 20 which are rounded to provide supports for the links of the chain. In the modification shown in Fig. 4, the sides 90 15 may be connected by a web joining the projections 19 and formed integral with the sides 15.

90

In assemblage the block of chain A having connection with the master link C is 95 positioned between the projections 19 of sides 15, and the free end portion of the chain is trained between the sides 15 so that the plates 7 of the chain ride upon the rounded supporting faces 20 of the section. 100 The space between sides 15 of link C, opposite from the projections 19 is relatively wider than the space between said projections, and is substantially the width of head 10, so that the abutments 13 are conveniently 105 positioned for engagement with the projections 9 of the chain.

105

When operating the wrench, the lever B is swung at substantially a right angle to link C moving the abutment 13 out of 110 proximity to the object D, such as a pipe, and thereupon the chain is trained about

the object with its free end portion extending between the sides 15 of link C, as hereinbefore described, the free end of the chain being pendants supported over the 5 blocks and plates of the chain adjacent its connection with said link. The lever B is then brought downwardly with its abutments 13 engaging projections 9 of the chain adjacent the link C. By bringing 10 pressure upon the lever B, the chain A is drawn tightly about the object, however, uniform pressure is brought upon its periphery due to the line contact of the blocks and plates of the chain with the external 15 periphery of the object. When it is desired to release the chain slightly from such engagement, the lever B is swung so that the abutments 13 move away from the pin 16. The object D, may be rotated, or 20 partly rotated, by oscillation of the operating lever, and movement of the chain A circumferentially about the axis of the object.

Changes in details may be made without 25 departing from the spirit and scope of my invention, but,

I claim:

A wrench comprising in combination, an

operating lever having on one end a pair of transversely spaced apart lateral projections curving outwardly and presenting concave faces outwardly of the end of the lever, a pair of master links pivotally connected to the opposite sides of said lever at said end thereof and having bosses on 30 their inner faces and at their free ends providing supports, and a chain comprising links and side plates connected by transverse pins projecting through and beyond the side plates, an end link of the chain 35 being secured between the bosses of said master links, and the free end of the chain being adapted to be trained over an object, through the space between the master links and over said bosses, the bosses supporting 40 the side plates at the free end of the chain in the path of said lateral projections of said lever, said lever being adapted to be swung in a direction to move the projections thereof toward the bosses, and engage 45 the adjacent pins of the chain outwardly of the links and in the concavities of the projections to draw the latter circumferentially about the object.

JOHN EVANS.
